ELECTRONIC TUBE

William W. Eitel, San Bruno, and Jack A. McCullough, Millbrae, Calif., assignors to Eitel-McCullough, Inc., San Bruno, Calif., a corporation of California

Application July 13, 1942, Serial No. 450,753

5 Claims. (Cl. 250—27.5)

Our invention relates to an electronic tube particularly adapted for transmission purposes.

It is among the objects of our invention to provide an improved structure of, arrangement for and mounting of the electrodes and leads in the envelope.

The invention possesses other objects and features of advantage, some of which, with the foregoing, will be set forth in the following description of our invention. It is to be understood that we do not limit ourselves to this disclosure of species of our invention, as we may adopt variant embodiments thereof within the scope of the claims.

Referring to the drawings:

Figure 1 is a perspective view of a tube embodying the improvements of our invention; and

Figure 2 is a vertical sectional view of the same.

In terms of broad inclusion, our tube comprises an envelope having a re-entrant stem at one end. A plurality of coaxial electrodes including a plate and grid and cathode are arranged in the envelope, the plate being provided with a cap at one end thereof. The plate is supported by a bracket on the cap secured to a lead disposed coaxially with the electrodes and sealed to the envelope end opposite the stem. The grid is supported on a lead sealed to a side of the envelope; and leads for the cathode are sealed to the stem.

In greater detail, and referring to the drawings, our tube comprises an envelope of glass or the like having a globe-like body 1 terminating at the top in a reduced neck 2 and at the bottom in a larger neck 3 carrying a re-entrant stem 4 having an exhaust tubulation 5. The envelope is fitted with a cup-shaped base 6, say of porcelain, secured to neck 3 by a suitable cement 7. Prongs 8 of the usual type project from the base.

Within the envelope are arranged a plurality of electrodes including a cathode 9, grid 11 and plate or anode 12. The plate is cylindrical in shape, and may be of any suitable metal, such as tantalum. It preferably comprises a plurality of arcuate sections with flanges welded together to form heat radiating fins 13. Annular beads 14 in the sections hold their shape when formed in a die. After welding, the fins are corrugated.

A hemispherical cap 15 of tantalum is secured over the upper end of the tubular plate by depending tabs 16 welded to the rim. Arched recesses 17 formed in the cap between tabs 16 provide vent openings. This cap protects the glass dome against electron bombardment, and also adds to the heat radiating surface of the plate structure.

Plate lead 18, preferably of tungsten, is arranged coaxially with the electrodes and projects through neck 2 at seal 19. A terminal button 20 is secured on the external end of this lead. The plate is supported by a bracket 21 welded at the lower end to cap 15 and at the upper end to lead 18. This bracket preferably comprises a pair of tantalum straps shaped with curved feet at the bottom to fit the cap for convenience in welding. The upstanding ends of the straps are grooved to embrace the lead, with laterally projecting portions providing heat radiating fins 22 extending along the lead.

One of the problems in tubes is to prevent heat 15 from flowing out to the glass and cracking the seal. Our structure overcomes this difficulty by reason of the mounting structure above described. As already mentioned, end cap 15 stops electron bombardment of the glass, and helps to dissipate 20 heat by radiation before it reaches lead 18. Fins 22 on the bracket also function to dissipate heat tending to flow out along the lead. Angularly disposed slits 23 in fins 22 serve to retard outward flow of heat by conduction. These features, together with the fact that tantalum is 25 not a good heat conductor, cooperate to thermally isolate the plate lead and its seal from the heat zone at the electrodes.

Another feature of the plate mounting structure is that a nickel sleeve 24 is interposed between tungsten lead 18 and the tantalum bracket. Nickel alloys or fluxes readily with both tungsten and tantalum, insuring a good welded joint between the parts. Furthermore, the weld 30 is clean and free of oxides and contamination which, if present, make outgassing difficult during evacuation.

Grid 11 is of the cage type, preferably of platinum wire, terminating in a tantalum base ring 40 26. This electrode is supported by a bracket 27 on a tungsten lead having an up-bent portion 28 and a transverse portion 29 extending through the envelope side wall at seal 31. This lead seal is preferably formed in the cylindrical wall of neck 3. Bracket 27 comprises a tantalum strap bent to embrace the upper end of lead portion 28 and having end tabs formed to fit grid ring 26, all parts being secured by welding. A nickel sleeve 32 is interposed between the bracket and lead to flux the weld at this point.

Filamentary cathode 9 comprises a coil of thoriated tungsten welded at top and bottom to a pair of tungsten leads 33 sealed to stem 4. Flexible extensions 34 connect the lower ends of 45 leads 33 with a pair of the base prongs 8.

We claim:

1. An electronic tube comprising an envelope, a plurality of electrodes including a plate and grid in the envelope, a lead sealed to an end of the envelope, a cap on one end of the plate, means on the cap supporting the plate on said lead, a lead sealed to a side of the envelope, and means supporting the grid on the last mentioned lead.

2. An electronic tube comprising an envelope, a plurality of coaxial electrodes including a plate and grid in the envelope, a lead coaxial with the electrodes and sealed to an end of the envelope, a cap on one end of the plate, means on the cap supporting the plate on said lead, a lead sealed to a side of the envelope, and means supporting the grid on the last mentioned lead.

3. An electronic tube comprising an envelope having a reentrant stem at one end thereof, a plurality of electrodes including a plate and grid and cathode in the envelope, a lead sealed to the other end of the envelope, a cap on one end of the plate, means on the cap supporting the plate on said lead, a lead sealed to a side of the envelope,

lope, means supporting the grid on the last mentioned lead, and leads for the cathode sealed to said stem.

4. An electronic tube comprising an envelope having a reduced neck at one end thereof carrying a re-entrant stem, a plurality of electrodes including a plate and grid and cathode in the envelope, a lead sealed to the other end of the envelope, a cap on one end of the plate, means on the cap supporting the plate on the lead, a lead sealed to a side of said neck, means supporting the grid on the last mentioned lead, and leads for the cathode sealed to said stem.

5. An electronic tube comprising an envelope, 15 a tubular plate open at one end thereof and disposed in the envelope, a cap on the other end of the plate, a lead sealed to an end of the envelope, means on the cap supporting the plate on said lead, a grid associated with the plate, a lead sealed to a side of the envelope, and means adjacent the open end of the plate supporting the grid on the last mentioned lead.

WILLIAM W. EITEL.
JACK A. McCULLOUGH.
